UNITED STATES PATENT OFFICE.

NELSON STAFFORD, OF NEW YORK, N. Y.

PENCIL-SHARPENER.

967,257.

Specification of Letters Patent. Patented Aug. 16, 1910.

Application filed January 18, 1909. Serial No. 472,778.

To all whom it may concern:

Be it known that I, NELSON STAFFORD, a citizen of the United States, residing in the borough of Brooklyn, in the county of 5 Kings, city and State of New York, have invented an Improvement in Pencil-Sharpeners, of which the following is a specification.

My invention relates to improvements in pencil sharpeners and the same is an improvement upon the device shown and described in Letters Patent of the United States, granted to me November 5, 1907, 10 #870,204, with the object as in other mechanical sharpeners to obviate the tedious 15 operation and smearing of the fingers usually attending the sharpening of a lead pencil with a pen-knife.

In the device of my present invention as in the device of my said patent, the cutting 20 blade is mounted on a carriage slideable and reciprocating on suitable guiding supports, and the edge of the blade is set at an angle to the line of its movement and this movement is at right angles to the axial line of 25 the pencil to be sharpened.

A revoluble holder is provided for the pencil, actuated by the carriage during the return of its reciprocating movement. The pencil is positively held in and to the holder 30 and the holder and pencil are automatically held during the sharpening operation. A fixed rest is provided for the pencil adjacent to the end being sharpened and which rest receives the thrust against the pencil in the 35 sharpening act.

The pencil holder is loosely mounted and of liberal area for pencils of different sizes, and all the parts are advantageously mounted on a tray or support receiving the cut- 40 tings of the wood and lead, all of which are hereinafter more particularly described.

In the drawing, Figure 1 is an elevation in partial section representing the device of my improvement. Fig. 2 is an elevation in 45 partial section in a direction at right angles to Fig. 1. Fig. 3 is a plan of the structure. Fig. 4 is an elevation and partial section at about the dotted line x, x , of Fig. 2. Fig. 5 is a vertical section of the pencil holding de- 50 vices longitudinally of the pencil and about on the dotted line y, y , of Fig. 4. Fig. 6 is a vertical section and elevation on about the dotted line z, z , of Fig. 2, and Fig. 7 is a plan of the cutting blade.

55 a represents the cutting blade which as shown separately in Fig. 7 is preferably tri-

angular in outline and provided with three cutting edges. This blade is mounted upon and adjustably secured to a sliding or reciprocating carriage composed of a bracket 60 plate b , the upright member b^1 , the inclined plate member b^2 , from one edge of which extends a cam plate b^3 ; and 2 represents lugs secured to the under surface and opposite edges of the inclined plate b^3 and receiving 65 at opposite sides the rods $c c^1$, which are the rods upon which the reciprocating carriage is movable.

d represents a base plate from one end of which rises the end plate d^1 , while from the 70 other end lugs d^2 extend upward, the respective ends of the rods $c c^1$ passing through and being riveted to the plate d^1 and the lugs d^2 .

The triangular cutting blade a is preferably provided with equi-distant holes 3 adapted to receive the end of a screw 4. This screw 4 extends through the bracket plate b to which it is secured, and its pointed end is adapted to pass into any 80 one of the three holes 3 according to the position of the plate, and the bracket plate b is preferably slotted and a screw-stem 5 passes through this slot and passes into the threaded aperture of a nut 6 while 85 the head on the screw stem 5 takes a bearing on the under side of the cutting blade. The nut 6 clamps the blade to the bracket plate and when it is desired to bring a fresh cutting edge into position the nut 6 is 90 loosened so as to release the cutting blade, and the screw 5 is moved through the slot so as to permit the cutting blade to be given a partial rotation to bring a fresh cutting edge into position, at which time the screw 4 95 will enter another one of the holes 3 and the nut 6 be tightened down again.

In order to change the inclination of the cutting edge of the blade a , I prefer to employ a pivot screw a^1 and a clamping bolt 100 a^2 ; the bolt passes through an opening in the bent portion of the bracket plate b and through a slot in the plate b^1 so that the lower end of the cutting blade may be raised or lowered as desired so as to change the inclina- 105 tion.

I employ a tray or support e provided as shown in Fig. 2, with grooves in the inner surface to receive the edges of the base plate d , in which said base plate carrying all of the 110 sharpening devices, is adapted to move, and situated beneath this base plate d and above

the lower portion of the tray or support e^1 is a drawer e^1 to receive the chips produced in sharpening the pencil.

I provide a U-shaped frame f , each upper right member of which is similarly apertured, and in connection therewith and preferably as a part thereof I provide a fixed rest f^1 to receive the pencil near the point thereof; the said rest f^1 occupying a position 10 at right angles to the upright members of the frame f . Within this frame f are frame plate members 7 and 8 provided with apertures of greater diameters than the diameters of the apertures of the upright members 15 of the frame f .

g represents a tubular holder through which the pencil to be sharpened is passed. This is of liberal aperture to receive pencils of different sizes and it is provided with a 20 thumb-screw 9 adapted to be brought against the surface of the pencil to hold the same in position. This tubular holder is provided with end-collars which are received in the apertures of the frame plate members 7 8 25 whereby the ends of the collar come against the inner surfaces of the upright members of the frame f , and in this way bearings are formed for the tubular holder g and end-wise movement prevented.

30 g^1 represents a pencil passing through the tubular holder g and on one end of this tubular holder there is formed or connected a ratchet wheel 10. Beneath the ends of the tubular holder g and against the inner 35 faces of the frame plate members 7 and 8, I provide shell members h and i ; in other words, plates with returned ends adapted to come against the inner faces of the plate members 7 and 8. These shell members together with the plate members 7 and 8 and the upright members of the frame f are all held together in the desired relationship by rivets 11.

40 The frame member f at one side is prolonged and formed with upright lugs $f^2 f^3$, through which a pin 13 passes. There is a spring h^1 in the shell member h , (see Fig. 6), which bears against the outer end of the tubular holder g , tending when the pencil 45 is in position to cause the periphery of the pencil to bear against the U-shaped frame member f at the aperture therein.

50 In the shell member i there is a pawl i^1 suitably pivoted and adapted to engage the teeth of the ratchet wheel 10; said pawl being held in position of engagement with said ratchet wheel by a spring 12.

55 A rocker arm k is pivotally mounted by the pin 13 on the lugs $f^2 f^3$, and while one end of the spring h^1 is connected to one of said lugs, the other end of the spring engages the rocker arm at a slot 14 formed therein, (see Fig. 4); the tendency of the spring being to elevate the rocker arm on 60 the one hand while the reciprocating move-

ment of the carriage and the cutter blade through the cam plate b^3 is to depress the rocker arm; said cam plate engaging the surface of a roller n connected through the pin 16 to the said rocker arm at its opposite end. This rocker arm k is carried upward (see Fig. 4), as a frame part and to the same is pivotally mounted a pawl l , the forward toothed end of which engages the teeth of the ratchet wheel 10; said pawl being held to place by a spring 15. A stop pin 18 limits the upward movement of the rocker arm k .

The tendency of the pawls i^1 and l and their springs 12 and 15 is to hold down the tubular holder and cause the pencil therein to rest snugly in the curved surface of the fixed rest f^1 .

The tendency of the spring h^1 Fig. 6, at the other end of the tubular holder g is to lift this end in opposition to the direction of pull of the pawls and their springs so that the tendency is to more firmly force the sharpened end of the pencil down into the fixed rest.

In the operation of the device hereinbefore described, the movement of the carriage and cutting blade from the position shown in Fig. 1, effects the cutting of a portion of the wood of the pencil in sharpening the same and the lead thereof, while the tubular holder and the pencil are held by the pawl i^1 and spring 12 against rotation. At the same time the movement of the cam plate b^3 off the roller n permits the spring h^1 to raise the rocker arm k and its pawl l , the same over-running the teeth of the ratchet wheel and at its upper movement taking a tooth. As the reciprocating carriage and cutter blade are drawn back from the extreme downward position to the position shown in Fig. 1, the cam plate b^3 acting upon the roller n forces the rocker arm downward and through the action of the pawl l turns the tubular holder and pencil to a predetermined extent, the pawl i^1 with this turning movement over-running the teeth of the ratchet wheel 10 in a position below that occupied by the pawl l , to a position where the pawl i^1 takes another tooth of the ratchet wheel to hold the same, the tubular holder and the pencil against the cutting movement in the opposite direction and the over-running tendency of the pawl l to turn the parts.

The base plate d^1 may be of any desired shape provided for the free discharge of the cuttings in sharpening the pencil from the surface of the plate d into the drawer or receptacle e^1 , from which they are periodically removed.

The operations hereinbefore described are continuously repeated with the sharpening of each pencil, and the position of the pencil may be quickly advanced to the position

desired by simply loosening the thumb-screw 9 and by hand forcing the pencil further through the holder. The inclination given to the cutting blade and the

5 bracket plate b by the pivot screw α^1 and clamping bolt α^2 determines the inclination of cut in sharpening the pencil according to whether the same is to be a long or short cut, at the pleasure of the operator.

10 I claim as my invention:

1. In a pencil sharpener, the combination with a reciprocating carriage and a cutting blade, of a revoluble loosely mounted pencil holding device, means for intermittently

15 turning the same, means for preventing the reverse turning movement of the pencil and the holding device by and during the sharpening operation, and means for providing a retarding friction to and for slightly tilting a 20 the pencil holding device and pencil.

2. In a pencil sharpener, the combination with a reciprocating carriage and a cutting blade, of a revoluble loosely mounted pencil holding device, means for progressively

25 turning the same, means for preventing the reverse turning movement of the pencil and the holding device by and during the sharpening operation, means providing a retarding friction to and for slightly tilting the 30 pencil, and a rest for the end of the pencil while being sharpened.

3. In a pencil sharpener, the combination with a reciprocating carriage including a bracket plate, of a triangular cutting blade 35 having a series of straight cutting edges for independent use and three apertures, means for clamping the said cutter blade to said bracket plate, and a screw device passing through the said bracket plate and adapted 40 to engage one of the openings of the said cutter blade and form an additional support.

4. In a pencil sharpener and in combination, a revoluble pencil holding device, a reciprocating carriage adapted for movement 45 at right angles to the axis of the pencil holding device, means positioned in line with the movement of the carriage and actuated thereby for turning the pencil holding device with a step by step movement and means for preventing the reverse turn-

ing movement of the pencil and the holding device by and during the sharpening operation.

5. In a pencil sharpener and in combination, a revoluble pencil holding device, bearing supports therefor, a ratchet wheel on one end thereof, a spring actuated pawl engaging the same, a spring-returned rocker arm and means for positively actuating the 55 same in one direction and a pawl mounted upon the rocker-arm and engaging the ratchet wheel for positively turning the revoluble pencil holding device, and a spring bearing upon the revoluble pencil holding 60 device for applying a friction to retard the turning movement of said device and for slightly tilting the same.

6. In a pencil sharpener, the combination with a tubular pencil holder having shouldered ends, of a frame apertured at its upper ends to receive the tubular pencil holder and against which the shouldered ends of the holder contact so as to form 70 bearings, shell members within the frame 75 plate members forming casings, and means for connecting the shell members to the upright members of the frame, a spring device in the casing formed by one shell member and a spring actuated holding device in 80 the casing formed by the opposite shell member.

7. In a pencil sharpener and in combination, a revoluble pencil holding device, bearing supports therefor, a ratchet wheel on 85 one end thereof, a holding pawl engaging the same, a rocker arm and means for positively actuating the same in one direction, a pawl mounted upon the rocker arm and engaging the ratchet wheel for positively turning 90 the revoluble pencil holding device, and a spring bearing upon the revoluble pencil holding device for applying a friction to control the turning movement of said device.

Signed by me this 30th day of December 95
1908.
